UNITED STATES PATENT OFFICE.

LESLIE HAYWOOD HOUNSFIELD, OF CROYDON, ENGLAND.

TWO-STROKE-CYCLE ENGINE.

Application filed January 30, 1923. Serial No. 615,801.

To all whom it may concern:

Be it known that I, LESLIE HAYWOOD HOUNSFIELD, a subject of the King of England, residing at Croydon, Surrey, England, ⁵ have invented certain new and useful Improvements in Two-Stroke-Cycle Engines, of which the following is a specification.

This invention relates to improvements in and connected with two-stroke cycle engines ¹⁰ of the three port type using crank chamber compression, and wherein the cylinders are connected in pairs at the combustion chamber end and so constructed that the piston movement alone, without the use of auxiliary valves, controls an inlet port between the carburettor and the crank-chamber, a transfer port leading from the crank-chamber to the combustion space, and an exhaust port leading from the combustion space to ¹⁵ the exhaust. In engines of this type the charge passes through the crank case before reaching the cylinders and in so doing is liable to pick up lubricating oil, even in engines in which lubrication is not effected by ²⁰ mixing the oil with the petrol or other fuel. If the oil thus picked up is not separated from the fuel but is allowed to collect in the cylinders, the engines and plugs are liable to become foul and oil is wasted. The ²⁵ present invention, therefore, has for its object the production of an engine which fouls less readily, and uses less lubricating oil than do engines as heretofore constructed.

In carrying out the invention the engine ³⁰ is so constructed as to afford the greatest possible opportunity for oil to separate and gravitate out of the charge into the crank chamber before the charge passes to the combustion chamber, and is further so constructed that such oil as may pass into the combustion space cannot remain there but must gravitate away therefrom and pass direct out from the exhaust. More particularly the engine is so constructed that the fuel passage from the carburettor to the crank chamber contains no liquid collecting pockets, and in addition is so constructed that the charge having entered the crank chamber (where the gas velocities are ³⁵ comparatively low) has to traverse it in an upward direction before reaching the transfer port from the crank chamber to the combustion chamber. Thus the bulk of the oil which separates out is caused to settle in ⁴⁰ the crank chamber, and by arranging the axes of the cylinders constituting each of the

connected pairs approximately horizontally, with the intake cylinder (i. e. the cylinder containing the piston which controls the new charge) above the exhaust cylinder ⁴⁵ (i. e. the cylinder containing the piston controlling the exhaust port), such oil as may enter the combustion space is promptly drained and blown away through the exhaust. ⁵⁰

In the accompanying drawings which show diagrammatically a four cylinder engine constructed according to this invention:—

Figure 1 represents a longitudinal section ⁵⁵ through the axes of two superposed cylinders (on the line 1—1 of Figure 2).

Figure 2 represents a cross section on the line 2—2 of Figure 1, and

Figure 3 is a section on the line 3—3 of ⁶⁰ Figure 2.

Like reference numerals indicate like parts throughout the drawings.

The transfer port or passage 10 leads from the upper part of the crank chamber ⁶⁵ 11 to the upper or intake cylinder 12, although not necessarily from the highest point of the crank chamber, as the highest point might be so situated as to collect lubricating oil thrown from the moving ⁷⁰ parts. By arranging the passage 10 in the upper part of the crank chamber the separation of oil by gravity is facilitated, and by suitably choosing the disposition of the transfer port with regard to the moving ⁷⁵ parts in the crank chamber, it is possible to ensure that oil cannot be thrown directly into the port. Any oil or excess fuel which may however pass through this transfer passage into the intake cylinder 12 readily ⁸⁰ gravitates through the intake cylinder into the exhaust cylinder 13, and thence out of the exhaust port 14 which is, in engines constructed according to this invention, situate in the lower side of the exhaust cylinder. ⁸⁵ The force of gravity is assisted by the intermittent rush of the gases passing through ⁹⁰ from the intake port to the exhaust port. ⁹⁵

Four cylinder engines constructed according to this invention consist conveniently of ¹⁰⁰ two two-cylinder units 15 and 16 arranged side by side so that the axes of the two intake cylinders 12 and 17 are substantially in a horizontal plane above another horizontal plane containing the axes of the ¹⁰⁵ exhaust cylinders 13 and 18. The inlet pipe or passage 19 from the carburettor may pass ¹¹⁰

in a substantially horizontal direction and about equidistant from the axes of all the cylinders into a chamber 20 containing ports 21 leading into the crank chamber, the ports 5 being controlled by the skirt ends of the exhaust pistons.

- The passage from the carburettor to the crank chamber is constructed so as to be free from pockets in which liquid can collect, 10 and so that any oil which may deposit drains down into the crank chamber, and by disposing the inlet pipe or passage 19 in the manner above described, the carburetted mixture becomes heated by reason of its proximity to the cylinders, or by passing through the water jacket, and this heating process, where the lubrication is effected by mixing lubricating oil with the fuel, further facilitates the separation of the lubricating oil. 15
- It will be noted that here again gravity and the rush of gases combined with the heating of the inlet pipe or passage, assist the separation of the lubricating oil and its deposition in the crank chamber.
- 20 Engines constructed according to this invention practically never foul their plugs, nor do they require de-carbonizing. Hence the difficulty experienced with most two-stroke engines, of obtaining sparking plugs 25 which can both resist oil and the high temperatures associated with such engines, is eliminated.

I claim:

1. In a two-stroke cycle internal-combustion engine of the three-port type having crank-case compression of the combustible mixture, the combination of a casing having a compression chamber in the form of a crank-case therein, an intake cylinder having a transfer port and an exhaust cylinder having an exhaust port within said casing, both of which cylinders open at one end into the said crank-case, a combustion chamber common to both cylinders at the end thereof remote from the crank case, the exhaust cylinder having an inlet port at the side of its exhaust port remote from the combustion chamber, a conduit connected to said inlet port for supplying combustible mixture thereto, a transfer passage putting the said transfer port in open communication with the crank-case, a crank-shaft in said crank case, and pistons operable one in each cylinder and operatively connected to said crank-shaft and arranged to control said ports, which said ports are so situated and the engine parts provided with said ports are so constructed that the combustible charge is compelled to flow to and through the inlet port to the transfer port along a path which drains downwardly towards the bottom of the crank-case away from the said conduit, and the whole of said combustion space in all positions of the pistons drains down from the transfer port to the exhaust

port without encountering a liquid-collecting pocket.

2. In two-stroke cycle internal-combustion engine of the three-port type having crank-case compression of the combustible mixture, the combination of a casing having a compression chamber in the form of a crank-case therein, an intake cylinder having a transfer port and an exhaust cylinder having an exhaust port within said casing, both 70 of which cylinders open at one end into the said crank-case, a combustion chamber common to both cylinders at the end thereof remote from the crank-case, the exhaust cylinder having an inlet port at the side of its exhaust port remote from the combustion chamber, a transfer passage putting the said transfer port in open communication with the crank-case, a crank-shaft in said crank-case, and pistons operable one in each cylinder and operatively connected to said crank-shaft and arranged to control said ports, which said ports are so situated, and the engine parts provided with said ports are so 75 constructed that the combustible charge is compelled to flow upwards in the crank-case from the inlet port to the transfer port along a path which drains downwardly towards the bottom of the crank-case away from the said inlet and transfer ports, and the whole of said combustion space in all 80 positions of the pistons drains down to the exhaust port without encountering a liquid-collecting pocket.

3. In a horizontal, two-stroke cycle, internal-combustion engine of the three-port type having crank-case compression of the combustible mixture, the combination of a casing having a compression chamber in the form of a crank-case therein, a pair of parallel substantially horizontal cylinders within said casing, whereof one cylinder is arranged above the other and both open at one end into said crank-case, a combustion chamber common to both cylinders at the end thereof remote from the crank case, the exhaust cylinder having an inlet port at the side of its exhaust port remote from the combustion chamber, a conduit connected to said inlet port for supplying combustible mixture thereto, a transfer passage putting the said transfer port in open communication with the crank-case, a crank-shaft in said crank case, and pistons operable one in each cylinder and arranged to control said ports, a crank-shaft in said crank-case, and means operatively connecting said pistons with the crankshaft, whereby the charge is compelled to flow from the inlet port to the transfer port along a path which drains downwardly towards the bottom of the crank-case away from the said inlet and transfer ports, and liquid-collecting pockets are obviated, substantially as described.

4. In a horizontal, two-stroke cycle, internal-combustion engine of the three-port

type having crank-case compression of the combustible mixture, the combination of a casing having a compression chamber in the form of a crank-case therein, a pair of parallel horizontal cylinders within said casing, whereof one cylinder is arranged vertically above the other, and both open at one end into said crank-case, a combustion chamber common to both cylinders at the 5 end thereof remote from the crank-case, the lower cylinder having an inlet port and at the side thereof remote from the crank-case an exhaust port, the upper cylinder having in its upper part a transfer port and a transfer conduit which communicates with the upper part of the crank-case, pistons operable one in each cylinder and arranged to control said ports, and means for controlling said pistons in unison, whereby the 10 charge is compelled to enter the compression chamber at a part thereof situated below the crankcase end of the transfer conduit, and the exhaust from the upper cylinder is compelled to pass through a part of the 15 lower cylinder on its way to the exhaust port without encountering liquid-collecting pockets, substantially as described.

5. In a horizontal, four-cylinder, two-stroke cycle internal-combustion engine of the three-port type having crank-case compression of the combustible mixture, the combination of a casing having two compression chambers each constituting a crank-case therein, two pairs of parallel horizontal cylinders arranged side by side within said casing, whereof the one cylinder of one pair is arranged above the other cylinder of the same pair and both cylinders of a pair open at one end into one of said crank-cases, 20 two combustion-chambers, one common to each pair of cylinders, at the end of the casing remote from the crank-case, the lower cylinder of each pair having only in its upper part a fuel-inlet port and in its lower 25 part at the side thereof remote from the crank-case an exhaust port, the upper cylinder of each pair having a transfer port which communicates with the upper part of the allotted crank-case, pistons operable one in each cylinder and arranged to control said ports, means for controlling 30 said pistons, a supply chamber for combustible mixture situated between said cylinders and opening directly into said inlet ports, the wall of which supply chamber is constituted in part by parts of the walls of 35 said cylinders, and a supply conduit for combustible mixture free from pockets lying between said cylinders and opening into said supply chamber, whereby the combustible mixture will be heated by the cylinders on its way to the latter, substantially as de- 40 scribed.

one in each cylinder and arranged to control said ports, means for controlling said pistons, a supply chamber for combustible mixture situated between said cylinders and opening directly into said inlet ports, and a horizontal supply conduit for combustible 45 mixture substantially parallel to the axes of the four cylinders and free from pockets lying between said cylinders and opening into said supply chamber, substantially as described.

6. In a horizontal, four-cylinder two-stroke cycle, internal-combustion engine of the three-port type having crank-case compression with the combustible mixture, the combination of a casing having two compression chambers each constituting a crank-case therein, two pairs of parallel horizontal cylinders arranged side by side within said casing, whereof the one cylinder of one pair is arranged above the other cylinder of the same pair and both cylinders of a pair open at one end into one of said crank-cases, two combustion chambers, one common to each pair of cylinders, at the end of the casing remote from the crank-case, the 50 lower cylinder of each pair having only in its upper part an inlet port and in its lower part at the side of said inlet port remote from the crank-case an exhaust port, the upper cylinder of each pair having a transfer 55 port which communicates with the upper part of the allotted crank-case, pistons operable one in each cylinder and arranged to control said ports, means for controlling 60 said pistons, a supply chamber for combustible mixture situated between said cylinders and opening directly into said inlet ports, the wall of which supply chamber is constituted in part by parts of the walls of 65 said cylinders, and a supply conduit for combustible mixture free from pockets lying between said cylinders and opening into said supply chamber, whereby the combustible mixture will be heated by the cylinders on its way to the latter, substantially as de- 70 scribed.

In testimony whereof I affix my signature.
LESLIE HAYWOOD HOUNSFIELD.
